UNITED STATES PATENT OFFICE

2,490,442

PROCESS FOR OBTAINING THE SUBTITLES
OF KINEMATOGRAPH FILMS

Nachoum Kagansky, Paris, France

Application January 15, 1947, Serial No. 722,193
In France January 22, 1946

1 Claim. (Cl. 41—41)

1

The invention relates to the process for obtaining the sub-titles of kinematograph films which comprises forming on the film an acid-proof "resist" (for example a layer of paraffin), eliminating the resist along the contour of the letters of the sub-titles by effecting an impression by means of typographic characters, preferably in the hot state, dissolving the silver of the emulsion layer at the places which have been exposed by the impression, and finally eliminating the resist.

The invention relates more particularly to dissolving the silver and aims at obtaining absolute transparency of the sub-titles by an operation of minimum duration.

In carrying out the above referred process, the silver is dissolved by placing the emulsion in contact with a nitric acid solution and the film is then washed. However, experience shows that it is difficult to eliminate completely the silver nitrate produced. This residual silver nitrate is decomposed by light and becomes yellow or black, so that the sub-titles, instead of being a pure white contrasting with the picture background, are yellowish, of faulty appearance and sometimes difficult to read.

It would be possible to treat the silver with hydrochloric acid and dissolve the silver chloride in sodium thiosulfate, but the conversion of the silver into silver chloride is too slow to enable a practical application of this process to be effected in a machine having an output which is acceptable from an industrial standpoint.

The process following the invention permits to obviate these difficulties by successively subjecting the silver of the emulsion to the action of a nitric acid solution, to the action of a hydrochloric acid solution, to washing with water, to fixing with sodium thiosulfate and finally to a final washing.

By operating in this manner the output of the machine is satisfactory and the quality of the sub-titles is substantially improved.

The accompanying drawing shows, by way of example, a diagrammatic arrangement for the application of the invention.

In this drawing, A designates the film to be provided with sub-titles, which has previously been coated with paraffin or other resist substance, in which the sub-titles have been printed by means of typographic characters, preferably in the hot state in order to facilitate the expulsion of the paraffin. Said film passes with a speed of 5 metres per minute over guide rollers 1, 2, 3, 4, 5,

6, 7, 8 and cylinders 9, 10 and 11, the cylinders 9 and 10 being partly immersed in a tank 12 containing a solution of fuming nitric acid at room temperature, and the cylinder 11 in a tank 13 containing a 60° Baumé hydrochloric acid solution. Free rollers 14, 15, placed in the loops of the film give it the requisite tension.

The thickness of the cylinders 9, 10 and 11 is equal to or slightly smaller than the width of the film between perforations, and as they rotate, said cylinders bring the reagents into contact with the emulsion face of the film. The nitric acid attacks the silver of the emulsion and the silver nitrate dissolves in the nitric acid of the tank 12. The nitrate which may remain adhering is then converted into chloride in the tank 13.

Jets of washing water are projected on to the loop of the film passing round the roller 15, as shown diagrammatically at 16. The film then passes into a sodium thiosulfate fixing bath, in which the residual silver chloride is dissolved, then into a final bath of washing water. The sub-titles thus obtained are absolutely transparent.

Of course, the invention is not limited to the practical details hereinbefore described which have only been given by way of example.

Having now described my invention what I claim as new and desire to secure by Letters 30 Patent is:

A process for obtaining the sub-titles of kinematograph films, which comprises forming on the emulsion layer of the film an acid-proof "resist," eliminating the resist along the contour of the 35 letters of the sub-titles by an impression by means of typographic characters, successively treating the silver of the emulsion layer first with nitric acid and then with hydrochloric acid separately, washing, fixing with sodium thiosulfate, 40 washing again, and finally eliminating the resist.
